UNITED STATES PATENT OFFICE

160,380

FIGURINE OR THE LIKE

William R. Galter, Chicago, Ill.

Application January 9, 1950, Serial No. 7,102

Term of patent 7 years

(Cl. D29—23)

To all whom it may concern:

Be it known that I, William R. Galter, a citizen of the United States of America, resident of Chicago, Illinois, have invented a new, original, and ornamental Design for a Figurine or the like, of which the following is a specification, reference being made to the accompanying drawing forming part hereof.

Referring to the drawing, Fig. 1 is a side elevational view of a figurine or the like showing my new design; Fig. 2 is a front elevational view; Fig. 3 is a top plan view; Fig. 4 is a side elevational view of the reverse side of my figurine or the like on a reduced scale; Fig. 5 is a rear elevational view on a reduced scale and Fig. 6 is a bottom view on a reduced scale.

I claim:

The ornamental design for a figurine or the like, substantially as shown.

WILLIAM R. GALTER.
